CURTAIN CONSTRUCTION

Edmond P. Bixer, New York, N. Y.

Application December 31, 1947, Serial No. 794,895

3 Claims. (Cl. 160—387)

1

This invention relates generally to curtains or similar window coverings, and more particularly to an improved type of window curtain in which the valance, heading, and body panel are integrated. A preferred form of curtain installation is one in which the curtain is of greater width than the window opening so that when the curtain is hung, it is gathered along the rod to produce a Shirred or draped effect. This is also true of the valance. It is among the principal objects of the present invention to provide curtain and valance structure in combination with a heading, in which the curtain and valance are pregathered along the upper edge thereof to produce a predetermined Shirred or draped effect even when the length of the rod is substantially equal to the length of the heading as fully extended.

A desired form of curtain installation is one in which a rod having curved ends is used. This projects the main central portion of the rod a substantial distance away from the window frame or building opening margin with which it is associated. This rod carries a valance having rounded ends, which are curved toward the wall or window frame upon which the rod is supported. When such construction is used, a second rod, located rearwardly of the first one, carries the upper edge of the curtain.

Another object of the present invention lies in the provision of structure of the class described where the head and valance extend beyond the lateral side edges of the curtain body panel so that a double hung curtain and valance effect is obtained with only a single curtain rod.

These objects and other incidental ends and advantages will more fully appear in the progress of this disclosure and be pointed out in the appended claims.

In the drawings in which similar reference characters designate corresponding parts throughout the several views:

Fig. 1 is a front elevational view of a curtain showing an embodiment of the invention.

Fig. 2 is a front elevational view corresponding generally to Fig. 1, but showing the curtain as hung upon a curved end rod which is of substantially equal length with respect to the heading element.

Fig. 3 is an enlarged fragmentary view in perspective of the upper left hand corner of Fig. 2.

Fig. 4 is a top plan view of Fig. 2.

Fig. 5 is an enlarged fragmentary vertical sectional view as seen from the plane 5—5 on Fig. 3.

In accordance with the invention, the curtain, generally indicated by reference character 10,

includes broadly a body panel element 11; a valance element 12; and a heading element 13.

The body panel element includes a top edge 15; a bottom edge 16; a left side edge 17 and a right side edge 18. The body panel element may be composed of any suitable sheet material to harmonize with or contrast with the remaining elements of the curtain.

The valance element 12 is elongated in character and generally horizontally disposed. The valance element 12 has a top edge 20, a bottom free edge 21, a bottom hem fold edge 22, a left side edge 23 and a right side edge 24. The valance element 12 is composed of flexible planar material, textile or homogeneous, and is of a length, between the edges 23 and 24, which is substantially in excess of the distance between the edges 17 and 18 when the body panel element 11 is in a flattened and extended condition.

20 The heading element 13 has a front free edge 27, a rear free edge 28, a top fold 29 and end or side edges 30 and 31.

The parts may be fabricated and connected to each other in different orders, as desired. There 25 follows here, by way of example, one manner of so doing. The heading element, in the form of an elongated strip is provided, along the edges 27 and 28, with edge hems produced by the rows of stitching 33 and 34, respectively, which reinforce 30 and prevent the raveling of said edges. After the element 13 is folded longitudinally about its central axis, said fold, indicated by reference character 29, forms the top edge of the finished curtain 19. Two elongated rows of stitching 36 and

37 join the front and rear portions 38 and 39, respectively, to form the heading member 40, the rod passage 41, the valance carrying member 42 and the body panel carrying member 43. The members 42 and 43 preferably extend downwardly 40 a substantially equal distance below the row of stitching 37.

The body panel element 11, at the upper edge 15 thereof is folded upon itself and secured by the row of stitches 45 to form an edge hem 46 which reinforces the upper edge of the panel 11. The upper portion of the body panel element 11, inwardly of the stitches 45 is gathered or Shirred, and is secured in such gathered or such Shirred condition upon the forward surface of the body carrying panel member 43 by the rows of stitching 46 and 47. The stitches 46 and 47 are disposed upwardly of the edge 28.

The valance element 12, at the upper edge 20 thereof is folded upon itself and secured by the row of stitches 50 to form an edge hem which

reinforces the upper edge of the valance 12. The upper portion of the valance element 12 inwardly of the stitches 59 and spaced a substantial distance therefrom to form the portion 51, is gathered or Shirred and is secured in such gathered or Shirred condition upon the forward surface of the valance carrying member 42 by the rows of stitching 56 and 57. The stitches 56 and 57 are disposed upwardly of the edge 27.

The bottom hem fold edge 22 is formed by the row of stitches 60, the latter serving to secure and reinforce the edge 21 of the valance element 12.

Since the distance between the edge 23 and the edge 24 of the valance element 12, when said element is in an extended condition, is greater than the distance between the edge 30 and the edge 31 of the heading element 13, said valance element 12 will always present a Shirred or ruffled appearance with respect to the heading element 13, even when said heading element 13 is fully extended longitudinally thereof.

Likewise, because the distance between the edge 17 and the edge 18 of the body panel element 11, when said element is in an extended condition, is greater than the distance between the points 70 and 71 of the heading element 13, said body panel element 11 will always present a Shirred or ruffled appearance with respect to the heading element 13, even when said heading element 13 is fully extended longitudinally thereof.

When the curtain is hung, it is placed upon a rod 80 of a well known type having curved ends 81 and 82. The heading element 13 is of a length, that is to say between the edges 30 and 31, which is at least substantially equal to the distance between the terminals of said rod in any adjusted position thereof, it being understood that the rod 80 is longitudinally adjustable in a telescopic manner. When so hung, the curtain 10 will appear as seen in Figures 2, 3 and 4, where the heading element 13 and the valance element 12 extend around to cover the rounded ends 81 and 82 of the rod 80, and to form a desirable finished or trim appearance for the lateral edges 17 and 18 of the body panel element 11.

The present curtain may be utilized desirably in different installations. For example, the present curtain may have a straight rod (lacking the curved ends 81 and 82), in which the terminals of the rod are located outwardly of the actual window opening, the edges 17 and 18 being coterminous with the lateral edges of the window opening. This will produce an effect seen in Fig. 1, where the heading and valance produce a double hung effect. This, therefore, produces an optical effect as if the heading and valance elements were hung from one rod and the curtain body panel element 11 were hung from a separate rod located rearwardly with respect to the rod which carries the heading element and valance element.

Where the length of the rod passage 41, that is to say the distance between the edges 30 and 31 is substantially greater than the length of the rod 80 upon which the curtain 10 is hung, the heading element 13 may itself be gathered longitudinally along said rod to increase the Shirring or draped effect. In the last mentioned type of installation, all three of the elements 11, 12 or 13 will be Shirred or gathered,

the excess fullness in the valance element and body panel element producing a luxurious and highly pleasing appearance.

By virtue of the fact that the gathering of the various elements with respect to each other is predetermined at the time of manufacture, the parts cannot become lost during washing and the laundering operation is simplified.

It may thus be seen that I have disclosed a novel and useful curtain construction which produces a double hung effect with a single rod and which, by its simplicity saves time both in manufacture, use and maintenance.

I wish it to be understood that I do not desire to be limited to the exact details of construction shown and described, for obvious modifications will occur to a person skilled in the art.

I claim:

1. Curtain construction comprising: a heading element of predetermined length having first and second lateral end edges; a body panel element, the upper portion of which is gathered and secured to said heading element, said body panel element having side edges which are spaced in the area of said gathering a distance which is substantially less than the distance between the end edges of the heading element.

2. Curtain construction comprising: a heading element of predetermined length having first and second lateral end edges; a body panel element, the upper portion of which is gathered and secured to said heading element, said body panel element having side edges which are spaced in the area of said gathering, a distance which is substantially less than the distance between the end edges of the heading element; and a valance element, the upper portion of which is gathered and secured to said heading element, said valance element having side edges which are substantially coterminous with the end edges of the heading element.

3. A window curtain comprising: heading element composed of an elongated strip of flexible sheet material having end edges and being folded upon itself to form a rod passage, the longitudinally free edge portions of said heading element forming downwardly extending valance and body panel carrying members, said valance carrying member being located forwardly of the body carrying panel member; a body panel element gathered and secured at the upper portion thereof to said body panel carrying member, said body panel element having side edges which in the gathered area thereof, are spaced from each other a distance which is substantially less than the distance between the end edges of the heading element; and a valance element secured at the upper portion thereof to said valance carrying member, said valance element having side edges which are substantially coterminous with the end edges of the heading element.

EDMOND P. BIXER.
